UNITED STATES PATENT OFFICE.

NATHANIEL LOMBARD, OF BOSTON, ASSIGNOR OF ONE-HALF TO HENRY A. CLARK, OF BROOKLINE, MASSACHUSETTS.

AUTOMATIC FIRE-EXTINGUISHING APPARATUS.

SPECIFICATION forming part of Letters Patent No. 514,155, dated February 6, 1894.

Application filed May 15, 1893. Serial No. 474,212. (No model.)

To all whom it may concern:

Be it known that I, NATHANIEL LOMBARD, a citizen of the United States, residing at Boston, in the county of Suffolk and State of Massachusetts, have invented certain new and useful Improvements in Automatic Fire-Extinguishing Apparatus; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to automatic fire-extinguishing apparatus, particularly that class called the dry system in which the water-distributing pipe sections contain water only in times of danger by fire.

My invention consists in improvements upon an invention relating to automatic fire-extinguishing apparatus of the above class described under Serial No. 473,061, filed in my name on the 5th day of May, 1893. This apparatus consisted in a main pipe with water distributing sections connected therewith, and an independent unbalanced valve for each section, together with mechanism for operating the valves by heat agency in order to extinguish incipient fires. In this invention the apparatus was in fact only semi-automatic, since after it was set in operation by the heat from a fire, it required manual adjustment in order to render it efficient to subdue another fire.

My present invention is embodied in improvements by which the apparatus is rendered entirely and completely automatic. Briefly stated, the apparatus is a dry system, and is composed of a main supply pipe, a series of water-distributing sections, and independent valves for each section, said valves being unbalanced and controlled in their positions each by an operating pipe connected with the main supply. Further in mechanism by which said operating pipe is opened by heat agency to change thereby the position of the independent valve and so supply water to the distributing pipe sections, conversely, upon cessation of such heat, to close the operating pipe, and so compel the press-

ure of the main system to shut the independent valve.

Other noticeable characteristics and functions of the several parts will be hereinafter fully set forth and explained.

The drawings represent in Figure 1 a vertical sectional elevation of a fire extinguishing apparatus, as applied to an apartment and embodying my invention. Fig. 2 is a plan of the same. Fig. 3 is a vertical section of the valve-case and valve enlarged. Fig. 4 is a similar view of the valve and valve case with a slight modification in the construction.

In said drawings I have shown automatic fire-extinguishing apparatus adapted for the several floors of a mill or business block. Each room, as shown in Fig. 1, contains the main supply pipe 2, which extends throughout the building; interconnected therewith are a series of water-distributing sections 3 composed of a branch tube 4 and laterals 5, either perforated or supplied with sprinklers 6. These sections are always open and empty except when a fire occurs. At such times they serve to distribute water supplied from the main by means of independent valves 7 one for each pipe section 3. In general apparatus of this class, to wit: the dry pipe system—has been semi-automatic, in other words it required manual adjustment after a fire in order to make it operative a second time. The gist of my invention is to render the apparatus completely automatic. To this end I provide a double piston unbalanced valve 7, the smaller piston 8 controls the passage from the main pipe to the open pipe sections 3. The larger piston 8' is to exceed in area the small one sufficiently to hold the latter closed against the pressure in the main supply pipe. Preferably in carrying out my invention I locate the piston 8' in a water-tight vessel 9, which has a differential supply and discharge. The supply consisting of a duct or small tube 10, which connects with the main 2, while the discharge is composed of a larger closed pipe 12, adapted to be opened by heat agency and closed upon removal or cessation of said heat factor.

To control the discharge pipe 12 I have located a valve 13 of any desired form, and fur-

ther supplied an operating pipe 14. This latter is preferably a hermetically sealed pipe to contain some highly volatile liquid; for every pipe section 3 I have supplied one of these 5 operating pipes, which may be extended in any direction in the room, where danger from fire is liable to occur. Thus it is evident, when a fire commences that the heat generated will volatilize the contents of the closed operating 10 pipe and create pressure therewithin. In order to utilize this force incited by the fire I have attached a Bourdon spring 15 at one end and united it with the valve-rod of the valve 13 in such manner that when a fire occurs said 15 valve is opened and water is allowed to discharge from the heretofore closed pipe 12. But as the latter allows water to pass away from the chamber in the vessel 9 faster than it can enter through the tube 10 the pressure 20 upon the piston 8' is reduced. The valve at once is forced from its seat by the pressure in the main and water from the latter rushes in and fills the water distributing pipe sections 3.

25 To close the valves 7 automatically after extinction of a fire I furnish small lugs or bosses upon the under face of the piston 8' or provide any other means by which to maintain a space for water therebeneath. Upon 30 cessation of the heat from the fire and cooling of the operating pipe 14 the pressure in the latter gradually diminishes as the volatile liquid again condenses. Movement of the Bourdon spring ensues and the valve 13 closes; 35 simultaneously therewith the duct supplies water to the chamber until the pressure of the main is again established, when the independent valve 7 is actuated and communication between said main and the water-distributing pipe sections 3 is cut off, leaving the latter empty as before the fire.

Within the chamber of the water-tight vessel 10 is located a check-valve 24, which prevents water passing back into the main should 45 the pressure in the latter be much reduced, or in the event of shutting off the water in the main, if repairs are needed. Thus the independent valves are all held in place, since the maximum main pressure is continued in 50 the vessel 10 at such times.

To carry off leakage from either valve should such take place, a recess is formed at 55 18 and a waste pipe 20 therefrom conducts the water away and prevents it from dropping to the floor, and causing damage.

What I claim is—

1. In automatic fire extinguishing apparatus, the combination with a main supply pipe, groups of open water distributing pipe sections, and independent unbalanced valves 60 for each section, of a water tight vessel having a differential supply and discharge, and a permanently closed pipe system for volatile fluid, said pipe system extending about 65 a structure or building to be protected and

adapted to open said discharge by heat agency and close the same upon cessation of such heat, whereby movement of the unbalanced valves occurs, substantially as specified.

2. In apparatus for extinguishing fires, the 70 combination with a main supply pipe, and branch sections of open pipes, a closed vessel connected with the main pipe, an unbalanced valve operated by the main pressure to prevent water from entering the open pipe 75 sections, a discharge fitted with a waste valve, and a permanently closed operating pipe to contain volatile fluid and extending about an apartment to be protected, and adapted to open and close said discharge, respectively 80 upon the presence or absence of heat units, substantially as and for purposes explained.

3. In automatic fire extinguishing apparatus, a main pipe, a series of open branch pipe sections, a water tight vessel having a 85 supply duct connected with the main, and a discharge pipe furnished with a waste valve, combined with a permanently closed operating pipe to contain volatile fluid and extending about a room in a structure to be protected, an unbalanced valve for each pipe section, and mechanism actuated by the closed operating pipe to shift the said waste valve, whereby the pressure in the water tight vessel is reduced or increased by the presence 90 or absence of heat units, and movement of the unbalanced valve is produced, substantially as described and stated.

4. The combination with a water-tight vessel having differential supply and discharge 100 pipes, and an unbalanced valve, the larger piston of which receives the pressure within the vessel, of a permanently closed operating pipe to contain volatile fluid and adapted to extend about an apartment in a building, 105 and mechanism actuated by the contents of the operating pipe to open and close the waste valve positively and automatically, substantially as stated.

5. In apparatus for extinguishing fires, a 110 main pipe, open branch sections, independent unbalanced valves for each section, and a water-tight vessel which contains the larger piston of each unbalanced valve, combined with a duct from the main to supply said vessel, a check-valve to prevent outflow of liquid 115 from said vessel to the main, a discharge pipe equipped with a waste valve, a permanently closed operating pipe extending about a floor of a building to be protected and to contain 120 volatile fluid, and a Bourdon spring which actuates the waste-valve, substantially as described.

In testimony whereof I affix my signature in presence of two witnesses.

NATHANIEL LOMBARD.
